LAMP SHADE

Rudolph A. Bushcott, Fort Atkinson, Wis., assignor to Thomas Industries Inc., Louisville, Ky., a corporation of Delaware

Original application Sept. 4, 1963, Ser. No. 76,470, now Design Patent No. 202,804, dated Nov. 9, 1965. Divided and this application Jan. 28, 1965, Ser. No. 83,808

Term of patent 14 years

(Cl. D48—16)

FIGURE 1 is a side elevational view of a lamp shade showing my new design;

FIGURE 2 is a plan view of the lamp shade of FIGURE 1;

FIGURE 3 is a view of a sector of the lamp shade of FIGURE 1, taken substantially along the line 3—3 in FIGURE 1, looking in the direction indicated by the arrows;

FIGURE 4 is a fragmentary sectional view, on an enlarged scale, taken substantially along the line 4—4 in FIGURE 3, looking in the direction indicated by the arrows; and

FIGURE 5 is a fragmentary sectional view, on an enlarged scale, taken substantially along the line 5—5 in FIGURE 3, looking in the direction indicated by the arrows.

It is to be understood that the partially shown pattern on the side of the shade in FIGURES 1 and 2 of the drawing continues uniformly throughout the broken line area thereof.

This is a division of my copending application, Serial No. D. 76,470, filed September 4, 1963, now patent No. D. 202,804.

I claim:

The ornamental design for a lamp shade, substantially as shown and described.
